US00D996062S

(12) **United States Design Patent** (10) **Patent No.:** **US D996,062 S**
(45) **Date of Patent:** **** Aug. 22, 2023**

(54) **SHOULDER STRAP**

(71) Applicant: **HERMES SELLIER (Société par actions simplifiée)**, Paris (FR)

(72) Inventor: **Pierre-Alexis Dumas**, Paris (FR)

(**) Term: **15 Years**

(21) Appl. No.: **35/513,494**

(22) Filed: **Aug. 2, 2021**

(80) **Hague Agreement Data**

Int. Filing Date: **Aug. 2, 2021**

Int. Reg. No.: **DM/215710**

Int. Reg. Date: **Aug. 2, 2021**

Int. Reg. Pub. Date: **Feb. 4, 2022**

(51) **LOC (14) Cl.** **03-01**

(52) **U.S. Cl.**

USPC **D3/327**

(58) **Field of Classification Search**
